UNITED STATES PATENT OFFICE.

FLORENCE F. CONNER, OF CLEVELAND, OHIO.

DESIGN FOR A BRIDLE-BIT SIDE BAR.

SPECIFICATION forming part of Design No. 29,703, dated November 22, 1898.

Application filed June 18, 1898. Serial No. 683,860. Term of patent 14 years.

To all whom it may concern:

Be it known that I, FLORENCE F. CONNER, of Cleveland, in the county of Cuyahoga and State of Ohio, have invented a new and original Design for a Bridle-Bit Side Bar, of which the following is a full, clear, and exact description, reference being had to the accompanying drawing, forming part of this specification, in which the figure is a perspective view of the side bar of the bridle-bit embodying my new design.

The design consists in a bridle-bit side bar consisting of a cheek or end bar of plate form, having a bit-bar secured within a hole in the same, this cheek having at one side of the bit-bar a hole or opening.

In the drawing, 2 represents the cheek,

and 3 the bit-bar, which extends through a hole therein and is secured by the bend 4.

5 is a hole in the cheek at one side of the 20 bit-bar.

6 is a ring portion of the cheek and 8 a snaffle. The bit-bar is bent at its other end, as shown at 7.

I claim—

The design for a bridle-bit side bar, substantially as herein shown and described.

In testimony whereof I have hereunto set my hand.

FLORENCE F. CONNER.
